CLAIM

The ornamental design for a substrate processing apparatus, as shown and described.

DESCRIPTION

FIG. 1 is a top, front, and left side perspective view of a substrate processing apparatus, showing our new design; FIG. 2 is a front view thereof; FIG. 3 is a rear view thereof; FIG. 4 is a top view thereof; FIG. 5 is a bottom view thereof; FIG. 6 is a right side view thereof; FIG. 7 is a left side view thereof; FIG. 8 is a cross-sectional perspective view taken along line I-I of FIG. 2, line II-II of FIG. 4, and lines III-III and IV-IV of FIG. 7, with an internal mechanism being omitted; FIG. 9 is a cross-sectional perspective view taken along line I-I of FIG. 2, line II-II of FIG. 4, and lines III-III and IV-IV of FIG. 7, with a lid closed, and with the internal mechanism being omitted; and, FIG. 10 is a cross-sectional view taken along line III-III of FIG. 7, with the internal mechanism being omitted. The dashed broken lines in the figures show portions of the substrate processing apparatus that form no part of the claimed design. The dot-dashed broken lines in the figures represent boundaries and form no part of the claimed design.
